UNITED STATES PATENT OFFICE

FERNAN OSCAR CONILL, OF CANNES, FRANCE

SAFETY RAZOR

Application filed November 22, 1928, Serial No. 321,105, and in France August 22, 1928.

In the ordinary common safety razors the cutting part of the blade rests upon a safety guard or comb but according to the inclination given to the handle by the person shaving himself, it may occur that only the comb touches the cheek and the blade stays more or less removed from the cheek. Further, as the hair cut away and the soap cannot pass between the blade and the comb, a more or less important greasiness will occur according to the beard and to the soap or cream used, thus hindering the blade to cut.

It will then be necessary to plunge the razor into water and even sometimes it will be necessary to take the razor to pieces for cleaning same.

For avoiding these inconveniences it has been already proposed to keep the blade separated from the comb by inserting a fixed piece, but such a separation, being favourable for a strong and full beard, will be quite inconvenient for a soft beard. Consequently if there is an advantage to space the blade sufficiently, there will be a danger to cut 25 the skin by spacing too much. Several factors may require the spacing of the blade, first the fullness of the beard and the consistency of the soap or cream, then the part of the face to be shaved, f. i. the mustache, 30 cheek, chin. The spacing of the blade will also be wanted if one desires shaving more or less near to the skin. Also the inclination given to the handle of the razor during shaving requires regulating of the space. Moreover this variable space is limited by the protection assured by the comb. Thus it is necessary to be able to regulate this space at 35 will.

The safety razor, the object of the present invention is characterized by the fact that the blade, either with one edge or with two edges is fixed to a supporting member independent from the comb but guided by the latter, and may be at will removed or spaced from the 40 comb or approached to same by a screw, said screw being placed at the end of the handle, and controlling a screw threaded stem rigidly connected to the support of the blade, said screw provided with an index or mark of 45 repair.

This arrangement is contrary to that of the razors hitherto known having the blade immovable resting upon the comb. The 55 razor according to the invention has the advantage of avoiding taking it to pieces for regulating the space of its blade, the latter being kept rigidly connected to the razor during regulation without modifying its curve or plane.

The spacing of the blade and the comb relative to one another is obtained only by rotating of a part of the handle. On the drawing some embodiments of the object of the invention are shown by way of example.

Fig. 1 shows a front view of the first form 60 with the upper part in section and removed from its seat.

Fig. 2 illustrates an axial section perpendicular to the view of Fig. 1.

Fig. 3 shows a front view of the second 70 form with parts in section.

Fig. 4 represents a longitudinal section through the third form, the lower part of the handle not sectioned.

Fig. 5 shows a first modification of a detail 75 i. e. of the teeth of the comb.

Fig. 6 shows a detail, to wit, a cramp for fixing the top plate to the blade support.

Fig. 7 shows a detail i. e. a modification of the vertical transversal section according to line VII—VII of Fig. 3.

To the upper part of the handle 2 of the safety razor a double comb 3 is rigidly connected. The interior of the comb 3 has a large groove 6 carrying a rectangular support 7, its upper surface 8 being curved and provided with two tenons 9 and a screw-threaded central pin 10. The cutting blade 11 rests on the surface 8 and is kept in its position by tenons 9. A head or top plate 12 curved at its lower part corresponding to the curved surface 8 covers and fixes the blade 11 at the same time curving the blade against the surface 8. The plate 12 and blade 11 are kept in place by a screw 14 to be screwed on the pin 10.

Beneath the support 7 a cylindrical shaft 15 (Fig. 2) is fixed, slidably within the interior of the handle 2. The lower part 16 of the stem 15 has a smaller diameter than the up- 100

per part, the free end of part 16 being screw threaded and carrying a nut member 17 forming the prolongation or lengthening piece of the handle. The part of this nut member 17 surrounding the screw threaded end of part 16 lies within the handle 2. A spring 18 surrounds the smaller part 16 of the shaft 15 and rests with one end against the upper end of the shaft 15 and with its other end against the nut member 17. The latter has a circular groove 20, into which a pin 19 fixed to the handle 2 projects.

After having fixed the blade in the same manner as with ordinary safety razors the blade 11 is removed from the teeth 4 of the comb by the support 7 on turning the screw 17 counter-clockwise without modifying the curve of the blade.

In Fig. 3 the support 21 for the blade 11 is guided during its movements by two tenons 22 fixed to the head or top piece 2 the upper part 29 of which covers the blade 11. These tenons or pins 22 pass through corresponding apertures in the comb 4. The regulating of the blade is the same as in Fig. 2.

In Fig. 4 the blade support 7 keeps a screw 25 screwed onto the screw threaded end 24 of the stem 16, the upper end of the screw 25 being widened according to a widened bore 30 in the support 7, thus not projecting over the curved surface 8 of the support 7. The end 24 has a larger diameter as the remaining part of the stem 16 and has been riveted or caulked with its utmost end 23 to the head or top piece 30.

The blade support 7 and the screw 25 are each lodged in a corresponding cavity of the comb and of the handle. This arrangement permits to have the front end of the razor wholly disengaged, thus not being hindered by projecting screws and the like during shaving. For a rapid regulation of the space between comb and cutting blade the lower part of the handle 2 adjacent to the screw 17 has been provided with a graduation 26, an index 27 permitting an accurate adjusting and bringing the blade back into its position wanted for use.

The blade support may be plain at its upper part for receiving flat blades, resilient or not. The comb could have only a single row of teeth as known for certain safety razors. The head of top plate may be fixed to the blade support by means of cramps or the like instead of being screwed thereto, such a cramp being shown in Fig. 6.

As shown in Fig. 5 the blade may entirely enter into a cavity 5 on the upper part of the comb 3, the edge of the blade being wholly protected by the teeth 4, the latter ones lying in the prolongation and same curved line as the blade 11. The cheek is indicated in dotted lines 34, 31, 33, 35 offering a continuously curved surface facilitating tensioning the skin and diminishing the risks of cutting,

whereas the cheek offers the curved line 34, 31, 36, 37 to a comb without the cavity for the blade and its edge thus tending to cut the skin and rendering shaving much more difficult.

According to the regulating of the blade 11 relative to the teeth 4 of the comb 3 a free space 39 will result in which the hairs of the beard and the foam may set fast. As shown in Fig. 7 this accumulation of impurities finds an issue by the apertures 38 in the bottom of the comb 3, these apertures corresponding with openings 40 provided in the support 7. The aforementioned impurities may escape through the space 39, openings 40 and apertures 38 whatever the distance of the blade 11 from the comb 3 or the teeth 4 may be.

Claims:

1. In a safety razor, the combination of: a handle; a comb on said handle; a blade; a curved blade support guided by said comb; a stem which passes right through said handle and is guided thereby, said stem carrying said support at one end; detachable means for clamping said blade against said support in an invariable position of curvature; and a nut member forming a prolongation of said handle and screwed on to the other end of said stem, substantially as and for the purposes set forth.

2. In a safety razor, the combination of: a handle; a comb on said handle; a blade; a curved blade support guided by said comb; a stem threaded at both ends, which passes right through said handle and is guided thereby said stem carrying said support at one end; a curved plate screwed on to the said end of said stem and clamping said blade against said support in an invariable position of curvature; and a nut member forming a prolongation of said handle and screwed on to the other end of said stem, substantially as and for the purposes set forth.

3. In a safety razor, the combination of: a handle provided with reference marks; a comb on said handle; a blade; a curved blade support guided by said comb; a stem which passes right through said handle and is guided thereby, said stem carrying said support at one end; detachable means for clamping said blade against said support in an invariable position of curvature; a nut member forming a prolongation of said handle and screwed on to the other end of said stem; and an index on said nut member co-operating with the reference marks on said handle, substantially as and for the purposes set forth.

4. In a safety razor, the combination of: a handle; a comb on said handle; a blade; a curved blade support guided by said comb; a stem threaded at both ends, which passes right through said handle and is guided thereby, said stem carrying said support at

one end; a curved plate screwed on to the said end of said stem and clamping said blade against said support in an invariable position of curvature; a nut member forming 5 a prolongation of said handle and screwed on to the other end of said stem; and means for preventing lateral movement of said curved plate and said blade, substantially as and for the purposes set forth.

10 In testimony whereof I have signed my name to this specification.

FERNAN OSCAR CONILL.
